DIESEL ENGINE

Newell O. Allyn, Los Angeles, Calif.

Application October 2, 1939, Serial No. 297,479

15 Claims. (CL 128—65)

My invention relates to a Diesel engine, and more particularly to a two-stroke-cycle Diesel engine. A principal object of the invention is to provide a radial engine of such character that will be materially reduced in weight and yet relatively high in horsepower.

Another object is to provide a series of sleeve valves in a series of cylinders so constructed as to operate in rotating and reciprocating directions, with respect to the longitudinal axis of the sleeve.

Still another object is to provide means whereby the ports are so arranged that an exhaust port may be opened prior to the opening of a scavenging port in a two-stroke-cycle internal combustion engine, but which closes at substantially the same time.

Subject matter which is shown but not claimed herein is covered by my co-pending application for patent, Serial Number 267,571, filed April 13, 1939.

The invention also comprises novel combinations and arrangements of parts, which will more fully appear in the course of the following description.

In the drawings, like reference characters designate similar parts in the several views.

Figure 1 is a diagrammatic view of the piston cycle and the accompanying valve action.

Figure 2 is a transverse section taken on the line 2—2 of Figure 4 showing supercharging ports closed.

Figure 3 is a vertical section showing all of the ports closed.

Figure 4 is a vertical section taken on line 4—4 of Figure 2.

Figure 5 is a reduced transverse section showing scavenging ports and tangential passages, taken on the line 5—5 of Figure 7.

Figure 6 is a transverse section showing the 40 exhaust ports partly open, taken on line 6—6 of Figure 7.

Figure 7 is a vertical section taken on line 7—7 of Figure 6.

Figure 8 is a transverse section showing supercharging ports open, taken on a line 8—8 of Figure 9.

Figure 9 is a vertical section taken on line 9—9 of Figure 8.

Figure 10 is a reduced transverse section taken on the line 2—2 of Figure 4.

Referring more in detail to the drawings, the reference numeral 27 designates a piston around which are disposed suitable rings 28. The piston 27 operates within an air-cooled cylinder 10, with

a cylinder head 11, so spaced as to allow the reciprocation of a sleeve valve 12 within the cylinder. Suitable rings 13 are disposed around the head 11. The cylinder 10 has (a) exhaust ports 14 around the upper portion, adjacent to the head 11, (b) supercharging ports 15 below the exhaust ports, and (c) scavenging ports 16 below the supercharging ports. These ports are preferably acute angle parallelograms, as shown in the drawings, and arranged in series around the cylinder.

The sleeve 12 has corresponding exhaust ports 17 and ports 18. The latter ports 18 are not only used as scavenging ports but also as supercharging ports, when the sleeve moves upward in a reciprocating and rotating motion, bringing the ports 18 in line with the supercharging ports 15 of the cylinder.

A housing 19 surrounds the exhaust ports 14 of the cylinder and has a discharge 22 into the atmosphere, in the direction of arrow G. A housing 20 surrounds the supercharging ports 15 of the cylinder and has a tangential connection 23 with a pressure blower 9. The air pressure enters the supercharging port housing 20 in the direction of the arrow H, tangential to the cylinder ports 15.

A housing 21 surrounds the scavenging ports of the cylinder and has tangential connections 25 and 26 at substantially opposite sides. The connection 25 connects with a blower 24 to supply air under a pressure relatively lower than the pressure introduced by the blower 9 to the supercharging ports. The air pressure in the connection 25 travels in the direction of the arrow I, tangential to the cylinder ports 16. The other connection 26 admits air in the direction of arrow J, from the slip stream that is passing around the engine during its forward propulsion. The tangential arrangement of the above-mentioned connections causes turbulence, to effect a thorough scavenging of the gases of combustion and a more intimate mixture of the fuel and air.

The exhaust ports 17 of the sleeve and corresponding exhaust ports 14 of the cylinder are 15 degrees of the crank angle, or piston cycle, wider than the ports 18 of the sleeve and the corresponding scavenging ports 16 of the cylinder, in order to accomplish the opening of the exhaust ports before the scavenging ports, in the reciprocation of the sleeve upon the power stroke of the piston. As heretofore mentioned, the exhaust and scavenging ports are arranged to be closed at the same time.

It will be apparent that exhausting the spent gases from the cylinder through the exhaust ports

simultaneously with the forcing of air into the cylinder through the scavenging ports causes a continuous outward flow of air and gases at the exhaust, thus scavenging the cylinder in the most efficient manner. The quantity of air that is thus forced into the cylinder is approximately twice its displacement. Ports that constitute a substantial portion of the circumference of the cylinder are only possible in a sleeve valve engine. The reason for having the ports around the cylinder is to accomplish a maximum scavenging effect. Poppet valve engines having inlet and/or exhaust openings in the head of the cylinder are required to have smaller opening areas, hence a more efficient scavenging effect is obtained with sleeve valves.

The foregoing embodiment may be used to carry out the following operation:

Referring to the drawings generally, but Figure 1 in particular, the point A represents the position of the piston 27 known as top dead center, at or about the time combustion takes place, beginning the power stroke. From this point the piston 27 moves downward. The sleeve 12 also moves downward in rotating and reciprocating directions with an elliptical motion, causing the exhaust ports 14 to commence to open at point B, 120 degrees down from point A. Maximum reciprocation of the sleeve 12 takes place at this time and 15 degrees later at point C, the scavenging ports 16 also commence to open. By the rapid reciprocation mentioned, the exhaust and scavenging ports are quickly opened and remain so until the piston 27 reaches point D in the cycle. At that point, the exhaust and scavenging ports close simultaneously, by reason of the maximum rotation of the sleeve, which takes place at this time. Thereupon, the reciprocation of the sleeve causes the sleeve ports 18, which were previously used as scavenging ports, to move upward in line with the supercharging ports 18 in the cylinder, thus opening the supercharging ports. The supercharging ports then remain open until the piston, moving upward on the compression stroke, masks or closes the same. This takes place at point E, approximately 75 degrees above bottom dead center.

All the ports in the cylinder are closed or masked, from point E to the point A, allowing compression of the fuel introduced by any suitable means.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications which may fall within the scope of the appended claims.

It is to be understood that in the hereunto appended claims, the words "aligned," "alignement," and words having the same root, are to be interpreted as including partial as well as complete alignment.

Having thus described my invention, what I claim and desire to secure by Letters Patent is:

1. An engine comprising a cylinder provided with scavenging, supercharging and exhaust ports, a piston in the cylinder, a sleeve valve between the piston and cylinder and provided with scavenging and exhaust ports, means to supply part of the slip stream to the scavenging ports in a direction tangent thereto, the piston and sleeve being movable in timed movements with

respect to each other, and the sleeve being movable for its scavenging port to be aligned with the supercharging port of the cylinder, in the cycle of operation.

5 2. An engine comprising a cylinder provided with scavenging and exhaust ports, a piston in the cylinder, a sleeve valve between the piston and cylinder and provided with scavenging and exhaust ports, means to supply part of the slip stream to the scavenging ports, blower means connected to simultaneously supply air pressure to the scavenging port of the cylinder tangential thereto, the piston and sleeve being movable in timed movements with respect to each other.

10 3. An engine comprising a cylinder provided with scavenging, supercharging and exhaust ports, a piston in the cylinder, a sleeve valve between the piston and cylinder and provided with scavenging and exhaust ports, a blower connected with the scavenging port of the cylinder, to supply air pressure thereto, a blower connected to supply relatively higher air pressure to the supercharging port of the cylinder, than the first-mentioned blower supplies to the scavenging port, the sleeve being movable to a position in which its scavenging port is aligned with the supercharge port of the cylinder in the cycle of operation and means connected to so move the sleeve.

15 4. An engine comprising a cylinder provided with scavenging, supercharging and exhaust ports, a piston in the cylinder, a sleeve valve between the piston and cylinder and provided with scavenging and exhaust ports, the sleeve being movable for its scavenging port to be aligned with the supercharge port of the cylinder in the cycle of operation the exhaust port of the sleeve being arranged to be out of alignment with all the cylinder ports when the scavenging port of the sleeve is aligned with the supercharging port of the cylinder, means connected to maintain the scavenging and exhaust ports of the cylinder closed when the supercharging port of the cylinder and the scavenging port of the sleeve are in register with each other and means connected to move the sleeve to the position in which its scavenging port is in register with the supercharging port of the cylinder.

20 5. An engine comprising a cylinder provided with scavenging, supercharging and exhaust ports, a piston in the cylinder, a sleeve valve between the piston and cylinder and provided with scavenging and exhaust ports, means to maintain said ports of the valves open to the scavenging ports of the cylinder at the same time during at least a portion of the operation of the engine, and to maintain the scavenging ports of the valve open to the supercharging ports of the cylinder during another portion of the operation of the engine, and means to supply to the cylinder through the scavenging port air in a volume approximating at least twice the displacement of the cylinder before the supercharging ports are opened.

25 6. An engine comprising a cylinder provided with series of scavenging ports, a series of supercharging ports and a series of exhaust ports, a piston in the cylinder, a sleeve valve between the piston and cylinder and provided with two series of ports, there being at least two ports in each series of ports and the plurality of each type being arranged in alignment with respect to the circumference of the cylinder and sleeve, the sleeve being movable from a position in which one of its series of ports is aligned with the scavenging ports of the cylinder to a position of alignment

ment of the same series with the supercharging ports of the cylinder, the other series of sleeve ports being arranged to be out of alignment with all cylinder ports in the latter position of the sleeve.

7. An engine comprising a cylinder provided with scavenging and exhaust ports, a piston in the cylinder, a sleeve valve between the piston and cylinder and provided with scavenging and exhaust ports, means connected to open the exhaust port prior to the scavenging port and to close the exhaust and scavenging ports substantially simultaneously.

8. An engine comprising a cylinder provided with scavenging, supercharging and exhaust ports, a piston in the cylinder, a sleeve valve between the piston and cylinder and provided with a scavenging-supercharging port and exhaust ports, the sleeve being movable to positions to open and close the exhaust and scavenging ports, and the scavenging-supercharging port in the sleeve being aligned with the supercharging port in the cylinder and the exhaust port of the sleeve being at the same time out of alignment with all cylinder ports during movement of the sleeve, and the piston being arranged to close the supercharging port in the cylinder and the scavenging-supercharging port in the sleeve by the piston masking same.

9. An engine comprising a cylinder provided with scavenging, supercharging and exhaust ports, a piston in the cylinder, a sleeve valve between the piston and cylinder and provided with scavenging and exhaust ports, means to supply part of the slip stream to the scavenging port in a direction at an angle to the radius of the cylinder, the piston and sleeve being movable in timed movements with respect to each other, the sleeve being movable to a position in which its scavenging port is aligned with the supercharge port of the cylinder in the cycle of operation, and means connected to so move the sleeve.

10. An engine comprising a cylinder provided with scavenging, supercharging and exhaust ports helically arranged, a piston in the cylinder, a sleeve valve between the piston and cylinder and provided with scavenging and exhaust ports, and means to effect elliptical movement of the sleeve to move the sleeve from a position in which the exhaust ports of the sleeve and cylinder are in alignment to a position in which the exhaust port of the sleeve is aligned with the supercharge port of the cylinder.

11. An engine comprising a cylinder provided with helically arranged ports, a piston in the cylinder, a sleeve valve between the piston and cylinder and provided with helically arranged ports, and means to effect elliptical movement of the sleeve to move the sleeve from a position in which at least one port of the sleeve is in alignment with a port of the cylinder, to a position in which said port of the sleeve is aligned with another port in the cylinder and at least one port

of the sleeve is out of alignment with all of the ports of the cylinder.

12. An engine comprising a cylinder provided with helically arranged ports, a piston in the cylinder, a sleeve valve between the piston and cylinder and provided with helically arranged ports, and means to effect elliptical movement of the sleeve to move the sleeve from a position in which at least one port of the sleeve is in alignment with a port of the cylinder, to a position in which at least one port of the sleeve is aligned with another port in the cylinder and at least one port of the sleeve is out of alignment with all of the ports of the cylinder.

15. An engine comprising a cylinder provided with helically arranged scavenging, supercharging and exhaust ports, a piston in the cylinder, a sleeve valve between the piston and cylinder and provided with scavenging and exhaust ports, the sleeve being mounted to reciprocate and to turn during the reciprocating movement, effecting movement of the sleeve ports in elliptical paths and producing different turning speeds of the sleeve at different points in the elliptical path, the exhaust and scavenging ports being arranged to be closed substantially simultaneously during a more rapid turning movement of the sleeve.

20. An engine comprising a cylinder provided with helically arranged scavenging, supercharging and exhaust ports, a piston in the cylinder, a sleeve valve between the piston and cylinder and provided with scavenging and exhaust ports, means to maintain the scavenging and exhaust ports open at the same time during at least a portion of the operation of the engine, means to supply air under pressure to the scavenging port when the exhaust port is open, the sleeve being mounted to reciprocate and to turn during the reciprocating movement, effecting movement of the sleeve ports in elliptical paths and producing different turning speeds of the sleeve at different points in the elliptical path, to retard and hasten opening and closing movements of the ports.

25. An engine comprising a cylinder provided with aligned scavenging and exhaust ports and supercharging ports out of line therewith, a piston in the cylinder, a sleeve valve between the piston and cylinder and provided with aligned scavenging and exhaust ports, a blower having its pressure outlet connected with the scavenging port of the cylinder, to blow air under pressure into the cylinder through the scavenging port, a blower connected to supply relatively higher air pressure to the supercharging port of the cylinder, than the first-mentioned blower supplies to the scavenging port, the sleeve being movable to a position in which its scavenging port is aligned with the supercharge port of the cylinder in the cycle of operation when out of line with respect to the scavenging port of the cylinder, and means connected to so move the sleeve.

NEWELL O. ALLYN.
